(57) **CLAIM**

The ornamental design for a warming tray and display, as shown and described.

DESCRIPTION

FIG. 1 shows a top perspective view of a warming tray and display;

FIG. 2 shows a bottom perspective view thereof;

FIG. 3 shows a front elevation view thereof;

FIG. 4 shows a back elevation view thereof;

FIG. 5 shows a top plan view thereof;

FIG. 6 shows a bottom plan view thereof;

FIG. 7 shows a left elevation view thereof;

FIG. 8 shows a right elevation view thereof; and,

FIG. 9 shows an exploded top perspective view thereof. That which is represented by broken lines illustrates environmental subject matter only and does not form part of the claimed invention.
